J. J. KILLALEE

SHOE

Filed August 18, 1924

FIG. 1.

FIG. 2.

FIG. 3.

INVENTOR
JOHN J. KILLALEE
White Port Shoes,
HIS ATTORNEY

UNITED STATES PATENT OFFICE.

JOHN J. KILLALEE, OF SAN FRANCISCO, CALIFORNIA, ASSIGNOR TO BUCKINGHAM & HECHT, OF SAN FRANCISCO, CALIFORNIA, A CORPORATION OF CALIFORNIA.

SHOE.

Application filed August 18, 1924. Serial No. 732,638.

The invention relates to apparel shoes. An object of the invention is to provide a shoe into which the entry of moisture or sand or other material from without the 5 shoe is prevented.

Another object of the invention is to provide means for preventing the entry of moisture into the shoe through the welt seam or other seams disposed adjacent the 10 lower portion of the shoe.

The invention possesses other advantageous features, some of which with the foregoing, will be set forth at length in the following description, where I shall outline 15 in full that form of my invention which I have selected for illustration in the drawings accompanying and forming part of the present specification. In said drawings I have shown one form of shoe embodying my 20 invention, but it is to be understood that I do not limit myself to such form, since the invention, as set forth in the claims, may be embodied in a plurality of forms.

In accordance with my invention, I prevent 25 the entry of moisture or sand into the shoe from without by forming a watertight lining within the shoe, such lining completely covering the insole and the vamp of the shoe so that moisture cannot enter 30 the shoe below the line of vamping.

The invention is disclosed in the accompanying drawings in which:

Figure 1 is a plan of one form of blank 35 which is lasted into shape to form the inner lining of the shoe.

Figure 2 is a phantom perspective view of one type of shoe showing the inner lining of my invention arranged therein.

Figure 3 is a vertical cross section through 40 the toe of a shoe provided with the inner lining of my invention.

In accordance with my invention, I arrange 45 within the shoe, a substantially watertight inner lining which completely covers the insole of the shoe and which extends upward within the shoe to any desirable height, preferably to at least as high as the line of vamping. This lining produces a substantially watertight supplementary shoe 50 within the shoe and since the stitching of the

shoe does not penetrate the inner lining, the lining is substantially watertight. The shape of the blank 2 from which the inner lining is formed, depends largely upon the style or character of the shoe and also depends 55 upon the height to which it is desired to carry the inner lining within the shoe. The blank 2 shown in the drawing is formed to extend upward in the shoe to the vamping. The vamping is the line of stitching 3 by 60 which the vamp 4 is secured to the quarter 5. The blank 2 is cut from a substantially watertight material such as soft, pliable leather, and is lasted on a suitable last, conforming to the size and style of the shoe to 65 be made. The outer edges 6 of the blank are brought together on the under side of the last and are secured together by a line of stitching 7. The seam thus formed is coated with a waterproof cement or other 70 suitable waterproof material to prevent the entry of moisture through the seam. The insole 8 is then adhesively attached to the underside of the lining and the shoe is then lasted and completed in the usual manner. 75

The inner lining 9 formed from the blank 2 completely covers the insoles 8 and completely covers the inner surface of the toe 12 of the shoe and extends backward along the sides or vamp or quarters of the shoe, 80 forming a watertight lining which completely surrounds the lower part of the foot when the foot is inserted in the shoe. This watertight lining may extend upward and constitute a lining for the quarters 5 or it 85 may terminate at the vamping. The waterproof lining is thus interposed between the welt seams and other seams disposed adjacent the lower portion of the shoe, so that moisture or sand or other material is prevented from entering the inside of the shoe and contacting with the foot, thereby providing a substantially watertight shoe into which the entry of water from without below the vamping is minimized. 90

I claim:

1. A shoe provided with the usual sole, insole and vamp, a one piece lining completely covering the inner surfaces of said insole and vamp and extending the entire length of 100

the shoe, a single seam in said lining overlying said insole, said lining being adhesively secured to said insole.

2. A shoe provided with the usual sole, insole and vamp, a one piece lining completely covering the inner surfaces of said insole and vamp and extending the entire

length of the shoe, a single waterproof seam in said lining overlying said insole, said lining being adhesively secured to said in-¹⁰ sole.

In testimony whereof, I have hereunto set my hand.

JOHN J. KILLALEE.
